W.H. Finckel

Attorney

UNITED STATES PATENT OFFICE

GEORGE A. KING, OF WATERBURY, CONNECTICUT, ASSIGNOR TO SCOVILL MANUFACTURING COMPANY, OF WATERBURY, CONNECTICUT, A CORPORATION OF CONNECTICUT

DOUBLE-POINTED PIN FASTENER

Application filed July 3, 1930. Serial No. 465,695.

This invention relates to pin fasteners, and particularly to pin fasteners which include a double-pointed pin and a shell or a cap, and has special reference to means for retaining the shell or a cap in predetermined position upon the pin.

The double-pointed pins referred to are of the type disclosed by the reissue patents of George Boden, George A. King and Lyman B. Chapman, No. 17,099, and George Boden and George A. King, No. 17,100, both dated October 9, 1928; and the shells or caps may take a variety of forms as indicated by the use to which the pin fasteners are to be put.

The object of the invention is to provide means on the shell or cap for positive engagement with predetermined portions of the pin, whereby the shell or cap is rigidly attached to the pin and its accidental separation therefrom or displacement relatively thereto prevented.

The invention consists in a pin fastener, comprising a double-pointed pin and a shell or cap. The pin has two legs bent to provide and joined by a U-shaped shell-engaging portion or bend arranged in substantial parallelism with and spaced from the legs, the spaces between the U-shaped portion and the legs forming at the bends provision for the reception of cooperative retaining means carried by the shell or cap, and the shell or cap thus held in fixed position on the pin, as will be hereinafter more particularly explained and finally claimed.

In the accompanying drawings illustrating the invention, in the several figures of which like parts are similarly designated, Figure 1 is a rear perspective view of a shell or cap provided with an embodiment of retaining means in accordance with the invention. Fig. 2 is a view similar to Fig. 1, but showing a double-pointed pin arranged for assembly of the shell or cap upon it. Fig. 3 is a rear perspective view of the completely assembled pin fastener. Figs. 4 and 5, are, respectively, a front and a rear elevation of the pin fastener of Fig. 3. Figs. 6 and 7 are, respectively, a front and a rear elevation of a pin fastener embodying the features of the invention, the

shell or cap of which is of the type to form the socket member of a separable fastener. Figs. 8 and 9 are, respectively, a front and a rear elevation of a pin fastener embodying the features of the invention, the shell or cap of which is of the type to form the stud member of a separable fastener.

As hereinbefore indicated, the pin fastener, no matter which of the various forms illustrated, or other conceivable forms, it may take, includes a double-pointed pin 1 and a shell or cap 2.

The double-pointed pin 1 comprises two pointed pin legs 3 joined by a U-shaped shell-engaging portion 4 which, as illustrated in Figs. 2 and 3, is bent into substantial spaced parallelism with the pin legs 3 throughout its side portions 5. The legs 3 and side portions 5 are joined and spaced apart by bends 6.

The shell or cap 2 has a face portion 7 provided with an offstanding or rearwardly extending marginal flange 8, and this flange carries pin-engaging means in the form of a bifurcated extension 9 which provides two deformable fingers 10 for engagement with the double pointed pin 1 at its bends 6.

The length of the U-shaped shell-engaging portion 4 from its joining bend to the bends 6 is such that it will fit snugly within the flange 8 and preferably in three point contact with it.

In assembling the shell or cap 2 upon the pin 1, the pin is arranged as illustrated in Fig. 2 with its U-shaped portion within the flange 8 and resting upon the rear of the face portion 7 of the cap. Then, by the use of appropriate tools, the extension 9 is depressed and its fingers 10 so deformed and diverged laterally that they extend into the spaces between the legs 3 and the side portions 5 of the U-shaped portion 4 and preferably in intimate engagement with the inner surfaces of the bends 6, as illustrated particularly in Fig. 3. Then a small section of the edge of the flange 8 is bent to form a depression in overlapping engagement with the bend of the U-shaped portion 4, as indicated at 11. Thus the shell or cap 2 is securely attached to the pin at three points and is thereby

rigidly held in predetermined fixed relation thereto.

Although in Figs. 1 to 5 inclusive the shell or cap 2 is shown as a plain cap, it is obvious that it may take the form illustrated in Figs. 6 and 7 in which an opening 12 is provided to form the socket member of a separable fastener, such as is disclosed in and covered by my copending application Serial No. 165,669, filed February 3, 1927. This opening 12 permits a complementary stud to engage with the side portions 5 of the pin with a resilient or snap action.

Also, instead of the forms of shell or cap just referred to, the shell or cap may carry the stud member 13 of a separable fastener, as shown in Figs. 8 and 9, and substantially as disclosed in the patent of Paul E. Fenton, No. 1,647,962, dated November 1, 1927.

If desired, any or all of the caps may be provided with a withdrawal-preventing prong 14 (see Fig. 9) which will, in addition, functionally replace the depression 11 of the edge of the flange 8 of the cap.

Various changes other than, and in addition to those hereinbefore particularly referred to are considered to be within the spirit of the invention and the scope of the following claims.

What I claim is:—

1. In a pin fastener, a pin and a shell, said pin having a pair of legs bent to form a shell-engaging member, and said shell provided with means arranged between said legs and adapted to be deformed laterally adjacent to the bent portions of said legs and between said legs and shell-engaging member.

2. In a pin fastener, a pin and a shell, said pin having a pair of legs bent to form a shell-engaging member, and said shell provided with a flange carrying an extension arranged between said legs and adapted to be deformed laterally adjacent to the bent portions of said legs and between said legs and the shell-engaging member.

3. In a pin fastener, a pin and a shell, said pin having a pair of legs bent to form a shell-engaging member, and said shell having a bifurcated extension providing deformable fingers adapted to be bent into engagement with the bent portions of said legs between said legs and shell-engaging member.

4. In a pin fastener, a double-pointed pin and a shell, said pin having two legs connected by a U-shaped bend provided with side portions spaced from said legs and joined thereto by bends, and said shell provided with a bifurcated extension adapted to be positioned between said legs and providing fingers deformable into engagement with said bends between said legs and side portions.

5. In a pin fastener, a double-pointed pin and a shell, said pin having two legs connected by a U-shaped bend provided with side portions spaced from said legs and joined

thereto by bends, and said shell provided with a bifurcated extension adapted to be positioned between said legs and providing fingers deformable by lateral divergence into engagement with said bends between said legs and side portions.

6. In a pin fastener, a double-pointed pin and a shell, said pin having two legs connected by a U-shaped bend provided with side portions spaced from said legs and joined thereto by bends, and said shell provided with a flange carrying a bifurcated extension adapted to be positioned between said legs and providing fingers deformable into engagement with said bends between said legs and side portions, a portion of said flange opposite said extension being bent into engagement with said U-shaped bend.

In testimony whereof I have hereunto set my hand this 2nd day of July, A. D. 1930.

GEORGE A. KING.
